UNITED STATES PATENT OFFICE.

WILLIAM E. HEFFNER, OF CANTON, OHIO.

DESIGN FOR A DISPLAY-RACK.

SPECIFICATION forming part of Design No. 23,450, dated July 10, 1894.

Application filed June 11, 1894. Serial No. 514,251. Term of patent 7 years.

To all whom it may concern:

Be it known that I, WILLIAM E. HEFFNER, a citizen of the United States, and a resident of Canton, county of Stark, State of Ohio, have 5 invented and produced a new Design for Display-Racks, of which the following is a full, clear, and exact description, reference being had to the accompanying drawing, making part of this specification.

10 The accompanying drawing is a view in perspective of the design.

My invention relates to a design for a display rack, and consists of the base A and vertical posts B, having extending therethrough 15 and therefrom, oblique arms C, in vertical order, said arms having therein annular recesses *a*, in which are placed display bars *b*, re-

ceding from the front in the order of elevation.

At the top portion of the rack is shown a 20 grille E, connecting the two posts B.

The leading features of my design are the base A, vertical posts B, oblique arms having annular recesses *a*, the bars *b*, and the grille E.

What I claim is—

25 The design for display rack herein shown and described.

In testimony whereof I have hereunto set my hand this 1st day of June, A. D. 1894.

WILLIAM E. HEFFNER.

Witnesses:

W. K. MILLER,
BURT A. MILLER.
